H. A. DOUGLAS,
PROJECTOR,
APPLICATION FILED DEC. 5, 1916.

Patented Jan. 14, 1919.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

PROJECTOR.

1,291,444.

Specification of Letters Patent.

Patented Jan. 14, 1919.

Application filed December 5, 1916. Serial No. 135,117.

To all whom it may concern:

Be it known that I, HARRY A. DOUGLAS, citizen of the United States, residing at Bronson, in the county of Branch and State 5 of Michigan, have invented a certain new and useful Improvement in Projectors, of which the following is a full, clear, concise, and exact description, reference being had to the accompanying drawings, forming a part 10 of this specification.

My invention relates to reflecting lamps employing dish-shaped casing and dish-shaped reflectors surrounded thereby, the reflecting surfaces being usually parabolic.

15 My invention has for one of its objects the provision of an improved mounting for a lighting element in front of the rear part of the reflector, and which mounting (a connector shell) extends backwardly to be accessible at the rear of the casing and has means for the purpose of adjusting the focus or lighting center of the lamp with respect to the reflector.

20 The invention has for another of its objects the provision of an improved assembly between the reflector and the casing therefor at the forward portions of these two elements of the lamp structure.

25 The invention has for its third object the provision of an improved means for mounting the light transmitting closure that is provided at the forward end of the lamp structure.

30 My invention, in all of its aspects, will be pointed out in the claim and will be fully described in connection with the accompanying drawing showing the preferred embodiment of the invention and in which Figure 1 is a view in longitudinal sectional elevation; Fig. 2 is a view on line 2—2 of Fig. 1; Fig. 3 is a view showing the preferred formation of the central portion of the reflector shell; Fig. 4 is a top plan view of a part of the structure shown in Fig. 1 with a portion 35 broken away; Fig. 5 is a view of an abutment which preferably enters into the construction; Fig. 6 shows a modification of the structure illustrated at the lower portion of Fig. 1 and in Fig. 4; and Fig. 7 is a bottom 40 view of a part of the structure shown in Fig. 6 with a portion broken away.

45 Like parts are indicated by similar characters of reference throughout the different figures.

50 The concave casing and the concave re-

flector shell 2 that projects into the casings are coupled at the forward end of the lamp structure, in accordance with the preferred embodiment of the invention. The means by which the coupling between the elements 55 1 and 2 of the lamp is effected are desirably in the form of a plurality of bayonet catches 3 distributed around and carried by one of the elements, preferably the casing 1, these bayonet catches operating as will herein- 60 after appear.

65 In the construction shown in Figs. 1 and 4 the bayonet catches 3 project through bayonet slots 4 provided in the rear continuation 5 of a retaining ring 7 which operates 70 to hold the casing and reflector shell together and which retaining ring is desirably curled over to form a hollow bead 8 that conceals the projecting ends of the bayonet catches. The reflector shell 2 is desirably 75 provided with a surrounding flange 9 integrally formed therewith and which flange is provided with an annular groove 10 that receives the packing cord 11. The light transmitting closure 12 is held against the 80 packing cord 11 at the front of the reflector by means of the retaining ring 7. When it is desired to remove the closure 12 and to separate the casing and reflector the retaining ring 7 is merely turned until the bayonet 85 catches 3 are disengaged from the bayonet slots 4 to permit the retaining ring to be removed. In the construction shown in Figs. 6 and 7 the bayonet catches 3 are provided upon the reflector shell and engage bayonet 90 slots 4¹ that are provided in the casing, this casing being backwardly curled as indicated at 1¹ to form a hollow bead that conceals the projecting ends of the bayonet catches. In the construction shown in Figs. 6 and 7, the 95 light transmitting closure 12 is permanently held between the packing cord 11 at the rear of the closure and the packing cord 13 at the front of the closure, this light reflecting shell 2 being inwardly curled at 14 to 100 hold the packing cord 13 in place. In the construction shown in Figs. 6 and 7 the reflector shell and back element are directly coupled by means of the bayonet catches 3¹ and the bayonet slots 4¹, but in the construction of Figs. 1 and 4 the casing and reflector shell are not directly coupled, the spring 18 operating to press the casing 1 and the reflector shell 2 apart at the rear portions of these elements, the spring 18 thus operating 110

to hold the reflector shell and glass 12 against the retaining ring 7, the retaining ring in turn coupling the forward ends of the reflector shell and casing.

5 The circuit connector shell 15 is provided at its front and rear end with means for attaching thereto circuit continuing devices, a lamp bulb being receivable at the forward end of the connector shell 15 and a plug at the rear end of the connector shell. The connector shell 15 has a threaded formation thereupon as indicated at 16, the threads at 16 being desirably formed upon an enlargement of the shell which may be 15 in the nature of a separately formed collar that is rigidly attached to the connector shell to form an integral or fixed part thereof. The threads 16 upon the connector shell have threaded engagement with a 20 sleeve 17 carried by the casing. This sleeve 17 is desirably tubular, the connector shell 15 passing through the bore of the sleeve 17 to be accessible at the rear of the sleeve 17 for attachment thereto of a circuit continuing 25 plug. Spacing intervenes between the forward end of the tubular adjusting sleeve 17 and the connector shell 15 for the reception of the rear end of the compression spring 18 whose forward end bears against 30 the rear end of the reflector shell 2. The rear end of the reflector shell is provided with an opening 19 in which the forward end of the connector shell 15 may move longitudinally of the axis of the lamp, the reflector shell carrying a tongue 20 that enters the slot 21 formed in the connector shell 15 to prevent rotation of this connector shell 15. The tubular adjusting sleeve 17 has a flange 22 formed therein that 35 engages the rear of the casing 1, the spring 18 maintaining the flange or enlargement 22 in engagement with the inner surface of the casing through the intermediation of the collar 16 and the threaded engagement of 40 this collar 16 with the adjusting sleeve 17 that is movable longitudinally of the lamp axis. In assembling the structure the tubular adjusting sleeve 17 is slipped rearwardly through the opening, provided at 45 the rear of the casing, longitudinally of the lamp axis, the flange 22 limiting the extent to which the sleeve 17 may be moved rearwardly and to maintain the sleeve in a fixed plane of rotation and in assembly with 50 the casing. When it is desired to adjust the lighting center or element 23 (which may be in the form of a filament within the lamp bulb 24) the adjusting sleeve 17 is turned to the right or left according to the direction in which the lamp bulb is to be moved, and inasmuch as the connector shell 15 cannot be turned owing to the engagement of

the tongue 20 in the slot 21 in the shell 15, the shell 15 must be moved backward or forward according to the direction of rotation of the adjusting sleeve 17, the spring 18 operating at all times to maintain the flange 22 in engagement with the casing 1 whereby not only will the adjusting sleeve 17 be prevented from shifting its position 70 longitudinally of the axis of the lamp portion but whereby also the adjustment of the lamp bulb effected by the rotation of the sleeve 17 will be maintained.

Claims relating to the construction and assembly of the casing, light transmitting closure, reflector shell, retaining ring, and other parts at the front of the lamp structure will be included in a division of this application: 75

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

A lamp including a concave casing; a concave reflector shell projecting into the casing, there being space between the rear ends of said casing and shell; a connector shell extending between the rear ends of the casing and reflector shell; a lamp bulb within the reflector shell and attached to the forward end of the connector shell; a rotatable adjusting sleeve slipped rearwardly through an opening which is formed in the rear end of the casing and having an enlargement engaging the inner surface of said casing to limit the extent to which the sleeve may be moved rearwardly and operating to maintain the sleeve in a fixed plane of rotation; means for preventing rotation of the connector shell and permitting longitudinal movement thereof to adjust the lamp bulb in or out, said connector shell being surrounded by the adjusting sleeve and in threaded engagement therewith to have in and out movement of the connector shell and the lamp bulb effected when the adjusting sleeve is rotated; and a spring engaging the rear end of the reflector shell and exerting rearward pressure upon the adjusting sleeve 100 to maintain engagement between the enlargement on the sleeve and the casing. 105

In witness whereof, I hereunto subscribe my name this 6th day of November, A. D. 1916.

HARRY A. DOUGLAS.
